UNITED STATES PATENT OFFICE.

FRANK K. DEKAN AND AUGUST GLAUBER, OF LORAIN, OHIO.

AUTOMATIC GATE FOR RAILWAY-CROSSINGS.

1,078,421.

Specification of Letters Patent.

Patented Nov. 11, 1913.

Application filed March 11, 1913. Serial No. 753,603.

To all whom it may concern:

Be it known that we, FRANK K. DEKAN, a subject of the Emperor of Austria-Hungary, and AUGUST GLAUBER, a citizen of the 5 United States, residing at Lorain, in the county of Lorain and State of Ohio, have invented certain new and useful Improvements in Automatic Gates for Railway-Crossings, of which the following is a specification.

This invention relates to automatic gates for railway crossings, and has for its object to provide improved operating mechanism for gates of the vertically tilting arm or 15 mast type, so that on the approach of a train the gates will drop, and after the passage of the train the gates will lift.

The invention is illustrated in the accompanying drawings in which—

20 Figure 1 is a plan view of a crossing and the gates beside the same. Fig. 2 is a perspective view showing a pair of gate boxes or supports at one side of the crossing. Fig. 3 is a front elevation of one of the 25 boxes, showing a signal bell. Fig. 4 is a side elevation of the same. Fig. 5 is a rear elevation of the same. Fig. 6 is a perspective view of one of the track boxes. Fig. 7 is a 30 side view showing the track levers and a slide operated thereby.

Referring specifically to the drawings, 6 indicates the rails and 7 are lever boxes or 35 housings located beside the same. Wires 8 are connected at opposite ends to slides 33, working in the boxes 7 on opposite sides of the crossing, the wires at one end passing around pulleys 9 to reverse the direction of movement. These boxes may be made in 40 sections and located a considerable distance from the crossing, and the wires will be carried on the guide pulleys 9^a to proper position for operating the gates. The wires are connected to levers 10 on cross shafts 12 extending between the gate boxes 13, and 45 on one side is a rod 11 between the levers 10, which operates both shafts when a wire 8 is pulled either way. A series of trip levers 29, sufficient in number and location to be at 50 all times engaged by one or more of the wheels of a train passing thereover, are pivoted in the box 7 and project at their lower ends into notches or recesses 34 in the slide 33, the recesses being so located and of such size that the levers will swing 55 freely when turned in one direction, but when turned in the other direction will

strike the bar 33 and shift the same lengthwise, thereby pulling on the corresponding rope 8. The trip levers and boxes are so arranged that when a train is passing in one 60 direction the levers in the box at one side of the track will operate, and when passing in the other direction the levers in the box at the opposite rail or side of the track will operate.

65 15 are turn buckles for adjusting the length of the cables 8.

The tilting masts of the gates are indicated at 14, pivoted at 17 in the gate boxes 13 and geared together as indicated at 16 70 for simultaneous operation over the roadway and side-walk. One mast 14 has attached thereto a lever 18 connected by a link 19 to a lever 20 on the end of the shaft 12 projecting into the bottom of the gate box, 75 and when said shaft is turned the levers are swung accordingly and the masts are raised or lowered.

The signal device consists of a bell 28 fastened to the front of the gate box and sounded by hammers 24 and 24^a which are pivoted to the box. One of these hammers, 24, is operated by its lower end tripping over the teeth of a ratchet 23, and the other is operated by a dog 26 tripping over the teeth of 80 another and opposite ratchet 23^a and striking a pin 25 at the lower end of the hammer 24^a. The ratchets 23 and 23^a are mounted on a shaft 35 which is turned by a segment 21 meshing with a gear 22 on said shaft 35, 90 the segment 21 being mounted on the shaft 12, to which a weight 27 is attached for the purpose of returning all the parts to their original position after each operation.

95 By the means described when the wheels of the train pass over each trip lever 29 at one side of the crossing it presses the same down and shifts the slide 33 which pulls the cable 8 and lowers the gates. After the train passes the crossing and reaches the 100 corresponding levers at the other side of the crossing the latter are pushed down to shift the slide and pull the cable the other way, thereby raising the gates. The turn of the shaft 12 causes the bell to sound as soon as 105 the gates begin to lower.

What we claim as new is:

1. In an automatic railway gate, the combination of a tilting gate bar, a shaft, operating connections between the shaft and the 110 gate bar, trip levers beside the track rails, at opposite sides of the crossing, slides

mounted for lengthwise movement beside the rails, and having recesses into which the levers project, to shift the same when the levers are operated, and cable connections between the slides and the shaft.

2. In an automatic railway gate, the combination of a tilting gate bar, a rock shaft extending across the railway track, operating connections between the shaft and the gate bar, casings located beside the track rails on opposite sides of the crossing, a series of trip levers mounted in said casings and projecting in position to be struck by wheels on the track, slides mounted for lengthwise
- 10

movement in the boxes and having recesses 15 into which the levers project, said recesses being shaped to permit the levers to swing in one direction without operating the slides, and to shift the slides when swung in the other direction, and cable connections between the slides and the rock shaft.

In testimony whereof, we do affix our signatures in presence of two witnesses.

FRANK K. DEKAN.
AUGUST GLAUBER.
